US00D579101S

(12) **United States Design Patent**
Whittenberger et al.

(10) **Patent No.:** **US D579,101 S**
(45) **Date of Patent:** **** Oct. 21, 2008**

(54) **HEAT EXCHANGER**

(75) Inventors: **William A. Whittenberger**,
Leavittsburg, OH (US); **Gordon W.**
Brunson, Chagrin Falls, OH (US); **John**
H. Becker, Atwater, OH (US)

(73) Assignee: **Catacel Corp.**, Garrettsville, OH (US)

(**) Term: **14 Years**

(21) Appl. No.: **29/280,520**

(22) Filed: **May 30, 2007**

(51) **LOC (8) Cl.** **23-04**

(52) **U.S. Cl.** **D23/386**

(58) **Field of Classification Search** **D23/386**,

(57) **CLAIM**

The ornamental design for a heat exchanger, as shown and described.

DESCRIPTION

FIG. 1 is a perspective view of a heat exchanger, showing our new design;

FIG. 2 is a bottom view thereof;

FIG. 3 is a front elevational view thereof;

FIG. 4 is a right side elevational view thereof;

FIG. 5 is a back elevational view thereof;

FIG. 6 is a left side elevational view thereof; and,

FIG. 7 is a top view thereof.
